Specification of Letters Patent

Patented July 28, 1914.

Application filed August 10, 1911. Serial No. 643,340.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has a number of objects and advantages in view.

One feature of my invention, as preferably embodied, comprises a telephone system which includes a common battery exchange to which telephone lines extend, a second common battery exchange to which other telephone lines extend, a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges, and means for removing the common battery of the second exchange from its normal relation with the link connector united with the trunk line at the second exchange to bring the common battery of the first exchange into operative association with said link connector at the second exchange.

Another feature of my invention resides in providing means for removing normal bridge connections at the second exchange from the composite telephone circuit between stations of connected lines that extend to the exchanges. When the exchanges are common battery exchanges the removal of the normal bridge connections enables the common battery at the first exchange to perform the functions that would otherwise be required of the common battery at the second exchange. I do not wish to be limited, however, to the employment of common battery exchanges in practising my invention.

In accordance with another feature of my invention the trunk line that intervenes between the exchanges is provided with a

switching mechanism for permitting it to be divided in separate sections, there being a magnet for governing said switching mechanism located upon that side of the trunk line that is in more immediate association with the telephone line of the second exchange and which magnet is within the control of the substation apparatus of a line extending to the second exchange to disjoint the trunk line.

There are other features of my invention which will be more fully hereinafter set forth.

I will explain my invention more fully by reference to the accompanying drawings in which—

Figure 1 illustrates a portion of an automatic telephone exchange system and a line extending thereto from an automatic subscriber's station; Fig. 2 illustrates, at its left hand end, a complemental portion of the automatic exchange illustrated in Fig. 1 and also shows a trunk line extending from the automatic exchange to a spring jack at the branch exchange together with a plug of a private branch exchange cord circuit inserted therein; Fig. 3 illustrates a link connector at the branch exchange and a local line extending from a telephone station to the branch exchange, Figs. 1, 2 and 3 being readable in connection with each other by placing the tops and bottoms of the sheets containing Figs. 1 and 2 together and the tops and bottoms of the sheets containing Figs. 2 and 3 together; Fig. 4 illustrates a portion of a manual exchange and a manual subscriber's line extending thereto; Fig. 5 illustrates at its left hand end a complemental portion of the manual exchange illustrated in Fig. 4 and also illustrates a trunk line extending from the manual exchange to the private branch exchange; and Fig. 6 illustrates a link connector at the private branch exchange and a private branch line extending from a telephone station to the private branch exchange, Figs. 4, 5 and 6 being readable in connection with each other by an assembly thereof similar to that above described in connection with Figs. 1, 2 and 3.

Like parts are given similar characters of reference throughout the different figures.

I will first describe the equipment illustrated in Figs. 4, 5 and 6, this being the simpler equipment. As illustrated in Fig. 4, each telephone line that extends from a

substation to a manual exchange is provided with two limbs 1, 2 intervening between the substation and the exchange and there terminating in tip and sleeve line springs 3 and 4 of a spring jack 5. A switch hook 6 is provided at each substation, the normal contact of this switch hook serving to include a condenser 7 and a signal bell 8 in bridge of the line sides 1 and 2 when the telephone receiver 9 is upon its switch hook, the alternate contact of said switch hook serving to include the telephone receiver 9 and the telephone transmitter 10 in bridge of the telephone lines when the switch hook 15 is relieved of the weight of the receiver. Each line is shown as being equipped with a cutoff relay 11, whose armatures when in normal positions serve to include a line relay 12 in serial relation with the sides 1, 2 of the associate line and a battery 13, circuit through the relay 12 being closed when the receiver 9 at the associate telephone station is removed from its switch hook, in a manner well known. A local circuit is 25 closed through a line signal device 14 by the relay 12 when this relay is energized in a manner well known. The circuit of the relay 12 includes the armature switches of the cutoff relay 11, this cutoff relay being 30 energized when a plug of a link circuit is inserted in the corresponding jack to open the circuit of the relay 12 to cause the armature of this relay to fall back and open the circuit of the line signal device 14, all 35 as is well understood by those skilled in the art. The link circuit shown in Fig. 4 is in the form of a plug ended cord circuit of a well known type, this cord circuit including an answering plug 15 and a connecting plug 16, the tip sections of these plugs being united by a tip strand and the sleeve portions by a sleeve strand. Each strand of the link circuit is rendered mettally discontinuous by a condenser 17 40 which preserves the continuity of its strand with relation to telephonic current. The answering end of the link circuit includes a relay 18 in bridge thereof while the connecting end of the link circuit includes a 45 relay 19 in bridge thereof, a battery, which may be the same battery 13, being common to the bridge conductors containing the relays 18 and 19 as illustrated. When a connection has been established, circuit through 50 the calling subscriber's relay 18 is completed through the calling subscriber's switch hook and the alternate contact of such switch hook, while circuit is closed through the called subscriber's relay 19 through the 55 switch hook at the called station and its alternate contact. The answering end of the link circuit is provided with a supervisory signal 20, in accordance with well known practice, that is included in a local 60 circuit that includes the common battery, a

plug contact and a jack contact engaged by the plug contact. The armature of the subscriber's relay 18 serves, when this relay is energized, to shunt the lamp 20 from circuit with the battery, this shunt being 70 broken when said relay is deenergized upon the relocation of the telephone receiver upon its switch hook whereby the lamp is caused to glow, the lamp being thereafter excluded from circuit by the mere withdrawal of the 75 answering plug from its jack. The connecting end of the link circuit is provided with a lamp 21 whose circuit is similarly governed by the connecting plug, the jack 80 engaging the same, the telephone apparatus at the private branch station illustrated at the right of Fig. 6 through the intermediation of connections with the connecting plug 16 in Fig. 4, certain connections shown in Fig. 5 and certain connections shown in Fig. 6 as will later appear. In Fig. 4 I have illustrated an operator's listening key 22 and an operator's ringing key 23 but have omitted the operator's telephone set and the generator as the association of these 90 elements is well understood.

The main exchange illustrated in Fig. 4 is provided with trunk line connections to enable the manual line to become connected with a private branch line, one such trunk line connection being illustrated at the left of Fig. 5 where there is shown the main exchange termination of a two way trunk line whose sides 24, 25 terminate in tip and sleeve line springs 26, 27 of a spring jack 28 located at the main exchange, the other ends of these trunk line sides terminating respectively in a tip line spring 29 and a sleeve line spring 30 of a trunk jack 31 located at the private branch exchange. The trunk 100 sides 24, 25 include, respectively, the normally separated contacts of the armature switches 32, 33, the contacts of these armature switches being closed when the relay 34 controlling the same is energized in the manner to be described. A suitable sort of signal 35, a drop being illustrated, is in bridge of the trunk sides at the branch exchange, the operator at the main exchange operating the signal device 35 by operating the ringing key 23. The operator at the private branch exchange responds to the signal conveyed at 35 by inserting within the trunk jack 31 either the answering plug 36 or the connecting plug 37 of a cord circuit that may be used for joining two private branch lines together, it being one object of my present invention to provide an improved system wherein such a cord circuit may thus be employed. Assuming that the plug 36 is 110 inserted within the jack 31, a local circuit is established through a magnet 38, which circuit may be traced from the grounded battery 39 through the winding of magnet 38 and the contacts 40 that are engaged as 120 125 130

a consequence of the insertion of the plug 36 in the jack 31. When the magnet 38 is energized its armature moves a star wheel 40¹ one step (the armature of magnet 38 when released assuming a position to enable it to move the wheel 40¹ another step upon another energization of the magnet 38) to turn the contact making wheel 41, mechanically coupled with the star wheel 40¹, one step. 5 This contact making wheel in moving one step first brings two contacts 42 together and thereafter permits the upper one of these two contacts to separate from the other as a consequence of its resilience. Thus the 10 sluggishly acting relay 43 is first energized and then deenergized consequent upon the insertion of the plug 36 in the jack 31, the energizing circuit being traceable from a grounded battery which may be the same 15 battery 39, through the winding of the relay 43, the contacts 42 when engaged, to ground. The lowermost armature switch of the relay 43 establishes a circuit for the sluggishly acting relay 34 at the trunk side gaps 32, 33, 20 the circuit then established for the relay 34 being traceable from a grounded battery which may be the battery 39, through the winding of the relay 34, thence to ground through the lowermost armature switch of 25 relay 43. The relay 43 also establishes a circuit, by way of its upper armature switch, that may be traced from a grounded battery, which may be the battery 39, through the sluggishly acting relay 44, contacts of the 30 upper armature switch of relay 43 to ground. The armature switch of relay 44, when operated, serves to close a gap in a bridge between trunk sides, which bridge includes a relay 45. Relay 45 is thereupon energized 35 owing to the fact that the battery 13 at the main exchange is now in bridge of the trunk sides 24 and 25 and is in circuit with the winding of relay 45 owing to the closure of the gaps 32, 33 in the trunk sides 24, 25. 40 When circuit is broken at 42, the circuit previously traced for the relay 34 is broken at the lower armature switch of relay 43, but a circuit closure in substitution for that previously occasioned at the lower armature 45 switch of relay 43 occurs at the armature switch of relay 46, the circuit then established for the relay 34 being traceable from the grounded battery 39 through the winding of the relay 34, the armature switch of relay 46 and the closed contacts 40, to ground, the armature switch of relay 46 being closed when the relay 45 is included in circuit since the relay 46 is in serial relation with the relay 45. The relay 34, being sluggish, affords ample opportunity for energization of the relays 44, 45 and 46 before the circuit for the relay 34 is broken at the lower armature switch of relay 43. The relay 43 being sluggish affords ample opportunity 50 for the energization of relays 44, 45 and 46 during the momentary closure of the contacts 42. The relay 44, having been energized, due indirectly to the momentary closure of circuit at 42, is to be included in another circuit for the purpose of maintaining 70 the circuit for the relays 45 and 46. To this end the lower armature switch of relay 43 establishes a closed local circuit through the relay 44 which is so apparent as not to require tracing. The relay 44 is made sluggish so that it will not respond when flashing occurs at either of two stations connected by way of the trunk line, circuit for the relay 44 opening at the lower armature switch of relay 45 as a consequence of such flashing 75 owing to the fact that the relay 45, as well as the relay 46, are not sluggishly acting. 80 The upper armature switch of relay 45 serves to establish circuit through a signal device 47 by a circuit which is so clearly 85 illustrated as not to require description, the device 47 displaying a signal until the called party answers or until the connection is taken down. The bridged relay 45 has its circuit opened, in a manner to be described, 90 when the called party responds, the serially related relay 46, however, remaining energized during the time the called subscriber has his telephone in use so that the circuit for the magnet 34 is not disturbed. The relay 46 is deenergized when the called party restores his telephone upon its switch hook or when the plug is removed from the corresponding jack 31. Another circuit is established which may be traced from ground 95 through the lowermost armature switch of 100 relay 34, the thimble of the jack 31, the heel of the inserted plug, the winding of relay 48, to a grounded battery, which may be the battery 39. The relay 48 thereupon operates its armature switches for the purpose of removing the grounded battery 39 and the ground 49 from connection with the talking sides of the link circuit shown in Fig. 6 so that these talking sides may be in 105 circuit relation with the battery 13 at the main exchange exclusively whereby the link circuit shown in Fig. 6, which is ordinarily adapted to the connection of private branch lines owing to the normal presence of the 110 battery 39 and ground 49, may be adapted to trunk line connection. Armature switches controlled by the relay 48 are introduced into circuit with the ground 49 and battery 39 to break the connections, under the circumstances described, of these elements with the strands of the link circuit, which connections were hitherto permanent. 115

The operations which have been described, excepting those which occur at the 125 called station, having been performed, the operator manipulates her listening key 50 to include her telephone set 51 in bridge of the strands of the cord circuit having plugs 36, 37 shown in Fig. 6. Assuming that the 120 130

subscriber's station illustrated at the left hand of Fig. 4 desires connection with the subscriber's station shown at the right hand end of Fig. 6, the operator will insert that plug of the two plugs 36, 37 which has not been inserted in the jack 31, into the jack 5 of the private branch line, and will thereafter operate the ringing key 52 or the ringing key 53 according to the plug employed.

10 When the called party responds his telephone is introduced in bridge between the sides of his line whereupon the relay 45, which is of high resistance, say 1,000 ohms, is shunted and is therefore deenergized whereby the relay 46 is placed within the control of the called party or the control of the operator, which latter control is exercised by the withdrawal of the plug from the jack 31. In this way the called party insures the breakage of the trunk conductor at 32, 33 when such called party restores his receiver upon its switch hook, the private branch exchange operator not being relied upon to accomplish this result. The 25 lowermost armature switch of relay 34 is released so that the relay 48 is deenergized to restore the normal connection of the battery 39 and the ground 49 with the link circuit shown in Fig. 6 to place the line signal 54 of the private branch line within the control of the called subscriber while his jack is still engaged by the plug to enable the called subscriber to signal the operator by removing his telephone from its switch hook, before the plug is removed from the jack. The signal device 54 is also a clearing out signal in that it is displayed during the absence of the receiver at the called station from the receiver switch hook and is inert when the receiver is restored upon its switch hook.

The battery 13 at the main exchange shown in Fig. 4 supplies battery current to the connected stations, the battery 39 at the 15 private branch exchange then taking no part in the supply of battery current to the branch exchange station; though the branch exchange is, as far as local branch exchange lines are concerned, a common battery system. It is of course understood that the manual exchange shown in Figs. 4 and 5 is a common battery exchange.

The armature switch of the relay 48 that governs the connection of the battery 39 also governs the connection of a relay 55 that is normally in bridge of the link circuit shown in Fig. 6 upon the answering end of that link circuit, the answering end being separated from the connecting end by a condenser 56. When the relay 48 is energized, the relay 55 is placed in shunt of the condenser 56 so that the tip strand of the associate cord circuit is rendered metallically continuous for the passage of straight current for the purposes which have been de-

scribed. In addition to the function of establishing a metallically continuous path about the condenser 56, the relay 55, when energized, serves to establish a circuit which may be traced from a grounded battery, 70 which may be the battery 39, through a resistance 57, say of 200 ohms, the armature switch of relay 55, the right hand armature switch of relay 48, to the listening switch contact 58, to connect coil 57 in parallel with a similar resistance coil 59. Under this condition, if the operator attempts to listen in to an established connection, relay 60, which is incapable of responding to the current flowing through one resistance coil is paralleled by another resistance coil, a sufficient increase of current then being afforded to operate the relay 60, it being understood that circuit through this relay 60 is closed at the contact 58 when the operator seeks to listen in. The relay 60 is marginal so that it will not operate if current is furnished through the relay by way of either resistance 59, 57 alone, but will operate if these resistances are in parallel relation with each other and in serial relation with the relay. These resistances are individual to each of the operator's keys at each operator's position and the uppermost contact of each of such keys at each position is connected with the relay 60 at such position, which relay at each position is common to such uppermost contacts of the operators' keys at the same position therewith. Such common connections are illustrated with these uppermost contacts in each of Figs. 3 and 6. By means of this equipment an operator is prevented from using the equipment of two cord circuits and the listening key ties pertaining thereto for the purpose of listening in upon 105 an established connection. When the relay 60 is effectively energized its upper armature switch establishes a short circuit across the terminals of the operator's telephone so that the operator cannot listen in. The lower armature switch of relay 60 when actuated will serve to establish a local circuit through a signaling device 61 to inform some one in authority that the operator is not making proper use of her facilities. When the 110 private branch exchange link circuit shown in Fig. 6 is used for connecting two local lines, the relay 55, then exclusively associated with the answering end of the link circuit and the relay 61 associated with the 115 connecting side of the link circuit, coöperate to prevent the operator from listening in upon an established connection, the relay 55 partially placing the resistance 57 in connection with the listening switch contact 58 due to the absence of the calling subscriber's telephone from its switch hook while the 120 relay 61 will complete the connection of the resistance 57 with said contact 58 when the 125 called subscriber's telephone is free of its 130

switch hook, with the result that the operator cannot listen in since the relay 60 will respond to exclude the operator's telephone from circuit when the operator actuates her listening switch for the purpose of including her set in circuit. In my application Serial No. 643,339, filed August 10, 1911, I have included claims which cover the secrecy feature thus described.

In the description thus far given, the station at the left hand end of Fig. 4 has been assumed to be the calling station and the station at the right hand end of Fig. 6 has been assumed to be the called station. If the latter station is the calling station, then the connection is initiated by the energization of the signal 54 upon the removal of the receiver from its switch hook at the calling station. The private branch operator will then insert a plug into the jack 5 of the local line and will insert the mate to said plug in the jack 31 that is free for use, whereupon the magnet 34 is energized in the manner which has been described to establish breaks 32, 33 in the trunk sides whereafter a signal is conveyed at the lamp 62 located at the main manual exchange due to a circuit which may be traced from a grounded battery, which may be the battery 13, through the relay 63, the upper armature switch of the cutoff relay 64 to the trunk side 24 and the metallic conductors that connect the same with the switch hook at the calling station thence through the telephone outfit at the calling station to the trunk side 25, and the lower armature switch of the cutoff relay 64 to ground. The circuit that immediately causes the signal lamp 62 to glow may be traced from the grounded battery 13 through the lamp to the armature switch of the relay 63. When the operator at the main exchange responds by inserting the answering plug 15 into the trunk jack 28, a circuit is established through the cutoff relay 64 which may be traced from the grounded terminal of said cutoff relay through the thimble of the jack 28, the heel of the answering plug 15, the supervisory lamp 20 to the grounded battery 13, whereby the signal 62 is included in open circuit and the signal it has previously conveyed is effaced. It will not be necessary further to describe the operations which occur when the call is initiated at a private branch station.

Referring now to Figs. 1, 2 and 3, I have shown equipment, associated with apparatus for effecting the automatic extension of telephone lines, for accomplishing the results which are accomplished by the equipment shown in Figs. 4, 5 and 6. In Fig. 1 and the left hand portion of Fig. 2 I have illustrated a line extending from an automatic telephone exchange to a substation, at which substation means are provided for effecting

the operation of the mechanism at the exchange automatically to effect the extension of the telephone line. At the substation shown in Fig. 1 I have illustrated a well known form of circuit interrupter 65 to be operated by a subscriber initiating a call for the purpose of automatically connecting the calling subscriber's line with a wanted extension thereof such as a trunk line that includes the talking sides 66, 67 and a local trunk line conductor 68 taking part in the control of the operation of the automatically operating line extending mechanism, all as is so well known to those skilled in the art as to require no further explanation. It has been assumed that the calling automatic subscriber desires communication with a private branch exchange line and that the calling subscriber has operated his circuit interrupting switch 65 for the purpose of connecting his line with the private branch exchange partially illustrated in Fig. 2. As a consequence of the automatic extension of the calling automatic subscriber's line, the signal 35 is operated as a result of the inclusion of the calling generator 69 in bridge of the talking sides of the trunk line, all in a manner well understood by those skilled in the art. The operator at the private branch exchange in response to the signal conveyed by the automatic calling subscriber at the signal 35 shown in Fig. 2 inserts the plug 36 of an idle link circuit in the jack 31 of the selected trunk line, whereafter operations are caused to ensue that are similar to the operations which have been described from this point on in the establishment of a connection between a calling main manual exchange line subscriber and a called private branch exchange line. I will therefore not describe the operations that occur from the automatic trunk signal 35 toward the called private branch line as such a description would be similar to that given between similar points in the establishment of a connection between the calling and called parties in the manual system shown in Figs. 4, 5 and 6. It will therefore be considered that the former description of this portion of the operation will apply to the equipment shown in Figs. 1, 2 and 3, characters of reference used in Figs. 4, 5 and 6 being applied to parts that are similar to parts shown in Figs. 1, 2 and 3.

In the equipment shown in Figs. 1, 2 and 3, the private branch exchange lines are adapted for connection with each other by link circuits having manually controlled ends 36 and 37, each line being provided with a signal 54 whereby the private branch operator may be made aware of the fact that one private branch line desires connection with another private branch line, a link circuit having the terminals 36, 37 that were hitherto described as forming a part of the

connection between a calling main line subscriber and a called private branch exchange subscriber being of service in connecting two private branch exchange lines. The signal 5 54 also serves to inform the private branch exchange operator that a private branch line desires connection with a line extending to some other exchange, a line extending to the automatic exchange being assumed to be 10 a line that may thus be desired by a calling private branch line. Assuming that a private branch line desires connection with a main line extending to an automatic exchange, the private branch calling party will 15 operate the signal 54 whereupon the operator will insert one or the other of the plugs 36, 37 in the jack of the calling private branch line, and will insert the mate of said plug in the jack 31. Each private branch 20 station may be equipped with a circuit interrupter 70 and each private branch trunk line section illustrated in Fig. 2 may be provided with a circuit interrupter 71, whereby the calling private branch party, 25 or the private branch operator, according to predetermination, may automatically select and connect the calling private branch line and the selected trunk 66, 67 with the link circuit similarly shown in Fig. 1 and 30 through said link circuit with the called automatic line, all as is so well known by those skilled in the art as to require no further explanation.

In view of the apparatus which I have 35 employed for connecting an automatic calling subscriber with a private branch called line, some details of equipment are supplied to enable me to employ my equipment when a calling private branch line is to be 40 come connected with a called automatic line, with the aid of the operator's interrupter 71, these additional characteristics not being necessary when the calling private branch party operates his calling switch 70. 45 When the operator manipulates the circuit interrupter 71 for the purpose stated, she first manipulates her switch 72 for cutting the circuit interrupter 71 into circuit with the portions of the trunk line extending to 50 the automatic exchange and thereafter separating these portions of the trunk line from the balance of the trunk line that belongs to the private branch exchange equipment, the switch 72 having normal follow-up contacts as illustrated. As a consequence of this operation of the switch 72, the relay 46 is deenergized with the result that the relay 34 is released, under the assumption 55 that the calling private branch party keeps his telephone off its switch hook. To restore the relays 46 and 34 to their energized condition the key 72 is provided with extra contacts 73 that perform, in a way, the function of contacts 42 when the 60 key 72 is operated, the contacts 73 estab-

lishing circuit through the relay 43 that indirectly causes the energization of the relay 34 in a manner which has been described in connection with Figs. 4, 5 and 6.

The automatic exchange is a common battery exchange, the common battery connection being illustrated at 75 when a private branch line calls an automatic line. The connection of this common battery is illustrated at 76 when the automatic line is a 75 calling line and the private branch exchange line is a called line. The common battery at the automatic exchange has its illustration repeated many times for the sake of simplicity, but it is understood that one 80 battery may serve all the purposes where battery current is required. By means of my invention the automatic exchange common battery supplies current not only to the automatic line but also to the private 85 branch line, the private branch link connectors having the private branch exchange common battery removed from normal association therewith to permit the common battery at the automatic exchange to replace the common battery at the private branch exchange and perform whatever 90 functions would otherwise be required of the common battery at the private branch exchange when a private branch line is connected with an automatic line either as a calling or called line. Thus my invention is of service in connection with an automatic exchange as well as with a manual 95 exchange.

It will be observed from what has been described and illustrated in connection with both systems shown in all of the figures that certain operating advantages are present when connection is effected between a 100 main line and a branch exchange line, it being stated in passing that I do not limit myself to exchanges that are strictly known as private branch exchanges when they are connected with lines extending to main exchanges by the apparatus and in the ways which have been described. I have chosen an operator controlled branch exchange as an illustration, as my invention finds special adaptability in connection with exchanges of that type. When a connection is effected between two exchange lines and the telephone receiver at the connected private branch station is removed from its hook, all bridges across the sides of the 105 composite telephone circuit at the private branch exchange are broken, the relays 46 and 55 being the only relays that will respond when the private branch telephone receiver is restored upon its switch hook. 110 These two relays being serially related and in circuit with the main exchange battery, and performing the functions which have been described. It may be said that if the line signal 54 is also to perform the func- 115 120 125 130

tion of a clearing out signal it, as an electromagnet, is also serially included in the line. By thus stripping the portion of the composite telephone circuit at the private branch exchange from continuous bridge connections I am enabled to avoid the faulty operation of the automatic equipment at the automatic exchange and the faulty operation of signals at the main manual exchange.

In the case of automatically established connections the private branch line may be provided with equipment that may serve automatically to connect such private branch line with a called automatic line. When a calling party at the station of a line connected with the private branch exchange desires to become connected with a subscriber whose line extends to the automatic exchange, such calling party will remove his telephone from its switch hook and operate his line signal 54 to secure the attention of the private branch exchange operator who is informed by the calling party of the number of the desired automatic exchange subscriber, the private branch operator having connected a link circuit with the calling line in response to the signal conveyed at 54. The operator connects this link circuit with an idle trunk jack at 31 so as to connect the calling line with a line leading to the automatic exchange. The calling subscriber may automatically extend his line at the automatic exchange into connection with the desired automatic line by manipulating the switch at 70 or the private branch exchange operator may do the same thing by manipulating the switch at 71 after the switch at 72 has been actuated to bring the switch 71 into circuit relation with the line extending to the automatic exchange. The relay 34, when released upon the deenergization of the magnet 46 upon the restoration of the telephone receiver of a connected private branch station, places the jack section of the trunk line at the private branch exchange out of such association with the balance of this trunk line at the private branch exchange that no device between the signal 35 and the private branch lines can be operated through the main exchange unless the key 72 of Fig. 2 is operated or the plug 36 of either Figs. 2 or 5 is withdrawn and reinserted in this jack with the results that are well understood from the previous description. In this way a main line subscriber, in again making connection with the trunk line, cannot, as a direct consequence, secure connection with a private branch line previously connected with that trunk line unless the key 72 or the plug 36 is manipulated as just described, these provisions being made to take care of these cases where the operator fails for some reason or other to take down the connection at 36 when a private branch line is through

with the trunk line. When a main line subscriber secures connection with the main line end of the trunk circuit, this end of the trunk circuit terminating in the armature switches 32, 33 of relay 34, the signal 35 is operated and the private branch station is not disturbed, the operator thereupon releasing the private branch line by removing the plug 36 from the jack 31 under the assumption that at this time no connection is to be established between such private branch station and the trunk line.

Prior to this time of the response of a called branch line subscriber a bridge is maintained by the relay 44, the high resistance relay 45 being included in this bridge and serving to maintain a signal at 47 during the maintenance of such bridge, the relay 45 being shunted by the private branch subscriber when he removes his telephone from its switch hook whereby the signal 47 is rendered inert. The private branch exchange operator is thus enabled to determine when the private branch subscriber removes his telephone from its switch hook, the signal 47 constituting a holding signal individual to its associate trunk to enable the operator to determine whether or not the trunk has been taken by the private branch exchange subscriber. When the connection has been concluded the lowermost armature switch of the relay 34 is restored to normal whereby the circuit of magnet 48 is opened to restore the battery 39 to its normal association with the link circuit at the private branch exchange shown in Figs. 3 and 6 whereby the signal 54 may receive battery to enable it to operate as a line signal in the event of the failure of the operator to remove the plug 37 from the jack of the private branch line before the private branch party attempts to make another call.

While I have herein shown and particularly described the preferred embodiment of the invention, I do not wish to be limited to the precise details of construction and circuit arrangement shown as changes may readily be made without departing from the spirit of my invention.

Having thus described my invention I claim as new and desire to secure by Letters Patent the following:—

1. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link-connectors at the second exchange for connecting lines extending to the second exchange and for connecting lines extending to the second exchange with the trunk line.

in the establishment of a connection between lines extending to the two exchanges; means for removing the common battery of the second exchange from its normal relation with the link connector united with the trunk line at the second exchange to bring the common battery of the first exchange into operative association with said link connector at the second exchange; and subscriber controlled means for restoring the common battery of the second exchange to its normal relation with the equipment thereat.

2. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges; means for excluding the common battery of the second exchange from circuit with the link connector united with the trunk line at the second exchange to bring the common battery of the first exchange into operative association with said link connector at the second exchange; and means controlled extraneously of the second exchange for restoring the common battery of the second exchange to its normal relation with the equipment thereat.

3. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges; means for removing the common battery of the second exchange from its normal relation with the link connector united with the trunk line at the second exchange to bring the common battery of the first exchange into operative association with said link connector at the second exchange; and a magnet brought into circuit with the common battery at the first exchange by the latter means to maintain this common battery in operative association with said link connector.

4. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges; means for releasing the common battery of the second exchange from circuit with the link connector united with the trunk line at the second exchange to bring the common battery of the first exchange into operative association with said link connector at the second exchange; and a magnet serving when released to effect the restoration of the normal relation of the common battery at the second exchange with said link connector.

5. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges; means for excluding the common battery of the second exchange from circuit with the link connector united with the trunk line at the second exchange to bring the common battery of the first exchange into operative association with said link connector at the second exchange; and a magnet brought into circuit with the common battery at the first exchange by the latter means to maintain this common battery in operative association with said link connector, said magnet serving when released to effect the restoration of the normal relation of the common battery at the second exchange with said link connector.

6. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange for connecting lines extending to the second exchange and for connecting lines extending to the second exchange with the trunk line in the establishment of a connection between lines extending to the two exchanges; means for removing the common battery of the second exchange from its normal relation with the link connector united with the trunk line at the second exchange; and a magnet brought into serial relation with the common battery at the first exchange by the latter means to maintain this common battery in operative association with said link connector, said magnet serving when released to effect the restoration of the normal relation of the common battery at the second exchange with said link connector.

7. A telephone system including a common battery exchange to which telephone lines extend; a second common battery exchange to which other telephone lines ex-

tend; a trunk line intervening between the exchanges to enable the establishment of a connection between a telephone line extending to one exchange and a telephone line 5 extending to the second exchange, there being link connectors at the second exchange for connecting lines extending to the second exchange and for connecting lines extending to the second exchange with the trunk line in the establishment of a connection 10 between lines extending to the two exchanges; means for excluding the common battery of the second exchange from circuit, with the link connector united with 15 the trunk line at the second exchange to bring the common battery of the first exchange into operative association with said link connector at the second exchange; and a magnet brought into serial relation with 20 the common battery at the first exchange by the latter means to maintain this common battery in operative association with said link connector, said magnet serving when released to effect the restoration of the normal 25 relation of the common battery at the second exchange with said link connector.

7. A telephone system including a common battery exchange to which telephone lines extend; a second exchange to which other 30 telephone lines extend; a trunk line intervening between the exchanges to enable the establishment of a connection between a telephone line extending to the first exchange and a telephone line extending to the second exchange, there being a link connector at the second exchange for 35 connecting lines extending thereto with each other and with the trunk line; means for removing normal bridge connections at the second exchange 40 from the composite telephone circuit between stations of connected lines that extend to the exchanges; and subscriber controlled means for restoring the normal bridge connections at the second exchange.

45 8. A telephone system including a common battery exchange to which telephone lines extend; a second common battery exchange to which other telephone lines extend; a trunk line intervening between the exchanges 50 to enable the establishment of a connection between a telephone line extending to one exchange and a telephone line extending to the second exchange, there being a link connector at the second exchange for 55 connecting lines extending thereto with each other and with the trunk line; means for removing normal bridge connections at the second exchange from the composite telephone circuit between stations of connected 60 lines that extend to the exchanges whereby the common battery at the first exchange may perform functions that would otherwise be required of the common battery at the second exchange; and subscriber con-

trolled means for restoring the normal 65 bridge connections at the second exchange.

9. A telephone system including a common battery exchange to which telephone lines extend; a second exchange to which other telephone lines extend; a trunk line 70 intervening between the exchanges to enable the establishment of a connection between a telephone line extending to the first exchange and a telephone line extending to the second exchange, there being a link connector 75 at the second exchange for connecting lines extending thereto with each other and with the trunk line; means for excluding bridges at the second exchange from the composite telephone circuit between stations 80 of connected lines that extend to the exchanges; and subscriber controlled means for restoring the normal bridge connections at the second exchange.

10. A telephone system including a common battery exchange to which telephone lines extend; a second common battery exchange to which other telephone lines extend; a trunk line intervening between the exchanges to enable the establishment of a 85 connection between a telephone line extending to one exchange and a telephone line extending to the second exchange, there being a link connector at the second exchange for 90 connecting lines extending thereto with each other and with the trunk line; means for excluding bridges at the second exchange from the composite telephone circuit between stations of connected lines that extend 95 to the exchanges whereby the common battery at the first exchange may perform functions that would otherwise be required of the common battery at the second exchange; and subscriber controlled means for restoring the normal bridge connections at the 100 second exchange.

11. A telephone system including a common battery exchange to which telephone lines extend; a second exchange to which other telephone lines extend; a trunk line 110 intervening between the exchanges to enable the establishment of a connection between a telephone line extending to the first exchange and a telephone line extending to the second exchange, there being a link connector at the second exchange for 115 connecting lines extending thereto with each other and with the trunk line; means for removing normal bridge connections at the second exchange from the composite telephone circuit between stations of connected lines that extend to the exchanges; and a magnet associated with the composite telephone circuit and in circuit with the common battery at the first exchange to maintain the changes 120 established in the bridge connections at the second exchange and serving when deenergized to permit the restoration of the nor-

- mal relation of the bridge connections at the second exchange.
12. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for removing normal bridge connections at the second exchange from the composite telephone circuit between stations of connected lines that extend to the exchanges whereby the common battery at the first exchange may perform functions that would otherwise be required of the common battery at the second exchange; and a magnet associated with the composite telephone circuit and in circuit with the common battery at the first exchange to maintain the changes established in the bridge connections at the second exchange and serving when deenergized to permit the restoration of the normal relation of the bridge connections at the second exchange.
13. A telephone system including a common battery exchange to which telephone lines extend; a second exchange to which other telephone lines extend; a trunk line intervening between the exchanges to enable the establishment of a connection between a telephone line extending to the first exchange and a telephone line extending to the second exchange, there being a link connector at the second exchange for connecting lines extending thereto with each other and with the trunk line; means for excluding bridges at the second exchange from the composite telephone circuit between stations of connected lines that extend to the exchanges; and a magnet associated with the composite telephone circuit and in circuit with the common battery at the first exchange to maintain the changes established in the bridge connections at the second exchange and serving when deenergized to permit the restoration of the normal relation of the bridge connections at the second exchange.
14. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for

excluding bridges at the second exchange from the composite telephone circuit between stations of connected lines that extend to the exchanges whereby the common battery at the first exchange may perform functions that would otherwise be required of the common battery at the second exchange; and a magnet associated with the composite telephone circuit and in circuit with the common battery at the first exchange to maintain the changes established in the bridge connections at the second exchange and serving when deenergized to permit the restoration of the normal relation of the bridge connections at the second exchange.

15. A telephone system including one exchange to which telephone lines extend; a second exchange to which other telephone lines extend; a trunk line intervening between the exchanges to enable the establishment of a connection between a telephone line extending to one exchange and a telephone line extending to the second exchange, said trunk line having switching mechanism normally dividing it into separate sections; and a magnet governing said switching mechanism and located upon that side of the trunk line that is in more immediate association with the telephone line of the second exchange that is connected with said trunk line and within the control of the substation apparatus of this telephone line of the second exchange, to join the trunk line sections when the latter telephone line is telephonically complete and to disjoint the trunk line when the latter telephone line is telephonically incomplete.

16. A telephone system including one exchange to which telephone lines extend; a second exchange to which other telephone lines extend; a trunk line intervening between the exchanges to enable the establishment of a connection between a telephone line extending to one exchange and a telephone line extending to the second exchange, said trunk line having switching mechanism normally dividing it into separate sections; a magnet governing said switching mechanism and located upon that side of the trunk line that is in more immediate association with the telephone line of the second exchange that is connected with said trunk line and within the control of the substation apparatus of this telephone line of the second exchange to join the trunk line sections when the latter telephone line is telephonically complete and to disjoint the trunk line when the latter telephone line is telephonically incomplete; a link connector for connecting the trunk line with said line of the second exchange; and means co-operating with the link connector to permit the magnet to break the trunk line into sections.

17. A telephone system including one exchange to which telephone lines extend; a second exchange to which other telephone lines extend; a trunk line intervening between the exchanges to enable the establishment of a connection between a telephone line extending to one exchange and a telephone line extending to the second exchange, said trunk line having switching mechanism normally dividing it into separate sections; a magnet governing said switching mechanism; a link connector for connecting the trunk line with a line extending to the second exchange; and means governed by the link connector for controlling the circuit of said magnet to divide the trunk line into sections when the magnet is deenergized and to merge said sections when the magnet is energized. 5 70 75
18. A telephone system including telephone lines extending to one exchange; telephone lines extending to a second exchange; a trunk line intervening between the exchanges; a link connector at the second exchange for connecting this trunk line with a line extending to the second exchange; a signal device individual to the line extending to the second exchange; an electro-magnet associated with the trunk line; a source of current for operating said signal device; and means governed by said electro-magnet for placing said source of current in association with said signal device while the line to which said signal device belongs is connected with the link connector to enable the operation of said signal device when the telephone at the associate telephone station is removed from its switch hook. 10 80 85
19. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being link connectors at the second exchange 15 90 95
- for connecting lines extending to the second exchange and for connecting lines extending to the second exchange with the trunk line in the establishment of a connection between lines extending to the two exchanges; means 20 100 105
- for removing the common battery of the second exchange from its normal relation with the link connector united with the trunk line at the second exchange to bring the common battery of the first exchange into operative association with said link connector at the second exchange; and means controlled by the subscribers whose lines extend to the second exchange for restoring the common battery of the second exchange to its 25 110 115
- normal relation with the equipment thereat. 30 120 125
22. A telephone system including one common battery exchange to which telephone lines extend; a second common battery exchange to which other telephone lines extend; a trunk line intervening between the exchanges to enable the establishment of a connection between a telephone line extending to one exchange and a telephone line extending to the second exchange, said trunk line having switching mechanism normally 35 125 130

the control of the substation apparatus of this telephone line of the second exchange to join the trunk line sections when the latter telephone line is telephonically complete and 5 to disjoint the trunk line when the latter telephone line is telephonically incomplete; a link connector for connecting the trunk line with said line of the second exchange; and means coöperating with the link connector to permit the magnet to break the 10 trunk line into sections.

23. A telephone system including one common battery exchange to which telephone lines extend; a second common battery exchange to which other telephone lines extend; a trunk line intervening between the exchanges to enable the establishment of a connection between a telephone line extending to one exchange and a telephone line extending to the second exchange, said trunk line having switching mechanism normally dividing it into separate sections; a magnet governing said switching mechanism; a link connector for connecting the trunk line with a line extending to the second exchange; and means governed by the link connector for controlling the circuit of said magnet to divide the trunk line into sections when the magnet is deenergized and to merge said 30 sections when the magnet is energized.

24. A telephone system including telephone lines extending to one common battery exchange; telephone lines extending to a second common battery exchange; a trunk line intervening between the exchanges; a link connector at the second exchange for connecting this trunk line with a line extending to the second exchange; a signal device individual to the line extending to the 35 second exchange; an electro-magnet associated with the trunk line; a source of current for operating said signal device; and means governed by said electro-magnet for placing said source of current in association with said signal device while the line to which said signal device belongs is connected with the link connector to enable the operation of said signal device when the telephone at the associate telephone station is 40 removed from its switch hook.

25. A telephone system including a common battery exchange to which telephone lines extend; a second exchange to which other telephone lines extend; a trunk line intervening between the exchanges to enable the establishment of a connection between a telephone line extending to the first exchange and a telephone line extending to the second exchange, there being a link connector at the second exchange for connecting lines extending thereto with each other and with the trunk line; means for removing 55 normal bridge connections at the second exchange from the composite telephone circuit between stations of connected lines that ex-

tend to the exchanges; and means controlled extraneously of the second exchange for restoring the normal bridge connections at the second exchange.

26. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for removing normal bridge connections at the second exchange from the composite telephone circuit between stations of connected lines that extend to the exchanges whereby the common battery at the first exchange may perform functions that would otherwise be required of the common battery at the second exchange; and means controlled extraneously of the second exchange for restoring the normal bridge connections at the second exchange. 75 80 85

27. A telephone system including a common battery exchange to which telephone lines extend; a second exchange to which other telephone lines extend; a trunk line intervening between the exchanges to enable the establishment of a connection between a telephone line extending to the first exchange and a telephone line extending to the second exchange, there being a link connector at the second exchange for connecting lines extending thereto with each other and with the trunk line; means for excluding bridges at the second exchange from the composite telephone circuit between stations of connected lines that extend to the exchanges; and means controlled extraneously of the second exchange for restoring the normal bridge connections at the second exchange. 95 100 105 110 115

28. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for excluding bridges at the second exchange from the composite telephone circuit between stations of connected lines that extend to the exchanges whereby the common battery at the first exchange may perform functions that would 120 125 130

otherwise be required of the common battery at the second exchange; and means controlled extraneously of the second exchange for restoring the normal bridge connections at the second exchange.

29. A telephone system including a common battery exchange to which telephone lines extend; a second exchange to which other telephone lines extend; a trunk line intervening between the exchanges to enable the establishment of a connection between a telephone line extending to the first exchange and a telephone line extending to the second exchange, there being a link connector at the second exchange for connecting lines extending thereto with each other and with the trunk line; means for removing normal bridge connections at the second exchange from the composite telephone circuit between stations of connected lines that extend to the exchanges; and means controlled by the subscribers whose lines extend to the second exchange for restoring the normal bridge connections at the second exchange.

30. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for removing normal bridge connections at the second exchange from the composite telephone circuit between stations of connected lines that extend to the exchanges whereby the common battery at the first exchange may perform functions that would otherwise be required of the common battery at the second exchange; and means controlled by the subscribers whose lines extend to the second exchange for restoring the normal bridge connections at the second exchange.

31. A telephone system including a common battery exchange to which telephone lines extend; a second exchange to which other telephone lines extend; a trunk line intervening between the exchanges to enable the establishment of a connection between a telephone line extending to the first exchange and a telephone line extending to the second exchange, there being a link connector at the second exchange for connecting lines extending thereto with each other and with the trunk line; means for excluding bridges at the second exchange from the composite telephone circuit between stations of connected lines that extend to the exchanges; and means controlled by the subscribers whose lines extend to the second exchange for restoring the normal bridge connections at the second exchange.

32. A telephone system including a common battery exchange to which telephone lines extend; a second common battery exchange to which other telephone lines extend; a trunk line intervening between the exchanges to enable the establishment of a connection between a telephone line extending to one exchange and a telephone line extending to the second exchange, there being a link connector at the second exchange for connecting lines extending thereto with each other and with the trunk line; means for excluding bridges at the second exchange from the composite telephone circuit between stations of connected lines that extend to the exchanges whereby the common battery at the first exchange may perform functions that would otherwise be required of the common battery at the second exchange; and means controlled by the subscribers whose lines extend to the second exchange for restoring the normal bridge connections at the second exchange.

In witness whereof, I hereunto subscribe my name this 24th day of July A. D., 1911.

MORTON L. JOHNSON.
